UNITED STATES PATENT OFFICE

125,926

DESIGN FOR A DRAPERY CORNICE

Karl F. Olson, Brooklyn, N. Y.

Application November 8, 1940, Serial No. 96,439

Term of patent 3½ years

To all whom it may concern:

Be it known that I, Karl F. Olson, a citizen of the United States, residing at Brooklyn, in the county of Kings and State of New York, have invented a new, original, and ornamental Design for a Drapery Cornice, of which the following is a specification, reference being had to the accompanying drawing, forming a part of this application.

Fig. 1 is a front perspective view of a drapery cornice showing my design; and

Fig. 2 is an enlarged front elevational view of either of the universal corner blocks shown in Fig. 1.

I claim:

The ornamental design for a drapery cornice, as shown.

KARL F. OLSON.
